UNITED STATES PATENT OFFICE

ALEXANDER D. KNEUPER, OF LOS ANGELES, CALIFORNIA, ASSIGNOR TO LOUISE KNEUPER

APPARATUS FOR LIFTING VISCOS FLUIDS

Application filed July 30, 1928. Serial No. 296,332.

My invention relates to a method of and apparatus for lifting viscous fluids and the method and apparatus herein described are particularly adapted for elevating low specific oils from wells.

It will be understood that under ordinary conditions it is practically impossible to lift relatively heavy or low specific gravity oils from wells, and in order to overcome this condition it has heretofore been the practice to heat low gravity oils in order to render them sufficiently mobile to be lifted by means of ordinary oil well pumping apparatus, but such practice involves considerable time, labor and expense.

It is the principal object of my invention to provide a relatively simple and easily practised method and likewise a relatively simple apparatus that may be economically and effectively used for lifting relatively heavy viscous fluids such as low gravity oils, and which method involves the use of an endless flexible carrier that is caused to pass through the body of viscous fluid in order that the latter may adhere to the carrier and be elevated to a convenient point where it is removed from the carrier and discharged into suitable tanks or containers.

With the foregoing and other objects in view, my invention consists in certain novel features of construction and arrangement of parts that will hereinafter be more fully described and claimed and illustrated in the accompanying drawings, in which:

Fig. 1 is an elevational view partly in section of a relatively simple form of apparatus that may be conveniently and economically employed in practising my improved method.

Fig. 2 is a vertical section taken through the center of a pulley and its supporting bracket that are positioned at the lower end of the well tube.

Referring by numerals to the accompanying drawings which illustrate a practical embodiment of my invention, 10 designates a suitable supporting frame that is arranged at the top of an oil well and journaled for rotation in bearings 11 that are mounted for vertical adjustment on the upper portion of said frame is a pulley 12. The pulley 12 is pro-

vided with suitable driving means (not shown). Journaled in the lower portion of the frame 10 is a pulley 13. Extending downwardly into the well hole is the usual well casing 14, and that portion thereof that is adjacent to the producing horizon is perforated as designated by 15 in order that oil may readily enter the chamber within said casing.

Extending downwardly through the casing 14 is the well tubing 16, the lower portion of which is perforated as designated by 17, and screw seated in the lower end of the tubing is a threaded nipple 18 that is formed integral with and which projects upwardly from one end of the top of a bracket 19.

Journaled in the bracket 19 is a pulley 20, and mounted for operation upon the pulleys 12, 13 and 20 is a flexible endless carrier, preferably a marlin covered cable 21.

The up-running portion of this flexible carrier passes from pulley 20 upwardly through the tubing 16, thence over pulley 12 and the down-running portion of said flexible member passes from the pulley 12 downwardly through the casing 14 to pulley 20. Pulley 13 serves as a support and guiding member to cause the down-running portion of the flexible member to travel downwardly through the casing 14 in a plane parallel with and adjacent to the tubing 16.

Secured within the upper portion of the bracket 19 is a short arm or finger 22 of resilient material, the free end of which bears lightly in the grooved periphery of pulley 20, and said finger functions as a scraper to remove sand or the like that might otherwise tend to accumulate within said grooved periphery and thereby interfere with the operation of the flexible carrier around said pulley.

The upper end of the tubing 16 terminates in front of frame 10 and projecting outwardly and upwardly from said frame a short distance above the upper end of the tubing is a bracket 23 through which passes the up-running portion of the flexible carrier 21, and arranged on said bracket is a scraper 24 that is designed to engage the surface of the carrier and remove therefrom by a brushing or scraping action the viscous fluid that

is elevated by the up-running portion of the carrier.

In practice my improved method with the apparatus herein illustrated and described 5 pulley 12 is rotated so as to cause the flexible carrier to travel from said pulley downwardly through the well casing around the pulley 20 at the lower end of tubing 16 and thence upwardly through said tubing to pulley 12, and during such operation the marlin 10 covered cable constituting the flexible carrier will pass through the relatively heavy oil that accumulates in the lower portion of the casing 14 and said oil, due to its viscosity, will 15 adhere to the up-running portion of the carrier and will, by such carrier, be elevated to the upper end of the apparatus where said oil will be scraped from the carrier and permitted to pass into suitable tanks or 20 containers.

Thus it will be seen that I have provided a relatively simple and practical method of and apparatus for lifting viscous fluids and particularly low gravity oils which cannot be 25 elevated from oil wells by the generally used pumping apparatus.

It will be understood that minor changes in the size, form and construction of the various parts of my improved method of and 30 apparatus for lifting viscous fluids may be made and substituted for those herein shown and described without departing from the spirit of my invention, the scope of which is set forth in the appended claims.

35 I claim as my invention:

1. The combination with an oil well tube, of a pulley located at the lower end thereof, a pulley located adjacent to the upper end of said tube, an endless flexible carrier arranged 40 for operation on said pulleys with the up-running portion of said flexible carrier passing through said tube and a scraper engaging the grooved periphery of said pulley between the down and up running portions 45 of said flexible carrier.

2. The combination with an oil well tube, of a pulley located at the lower end thereof, a scraper engaging the grooved periphery of said pulley at the top thereof, a pulley located 50 adjacent to the upper end of said tube, an endless flexible carrier arranged for operation on said pulleys with the up-running portion of said flexible carrier passing through said tube, and means located adjacent to the upper end of the tube for removing oil that adheres to said flexible carrier.

3. The combination with an oil well tube, the lower end of which is perforated, of a frame carried by the lower end of said tube, 60 a pulley arranged for operation within said frame, a pulley arranged adjacent to the upper end of the well tube, an endless flexible carrier arranged for operation on said pulleys with its up running portion passing 65 through said tube and a scraper carried by 70

said frame and engaging the grooved periphery of the pulley at the lower end of the tube between the down and up running portion of the flexible carrier.

In testimony whereof I affix my signature.

ALEXANDER D. KNEUPER.
